[57] CLAIM

The ornamental design for a glove box organizer or similar article, as shown and described.

DESCRIPTION

FIG. 1 is a front perspective view of a glove box organizer showing my new design;

FIG. 2 is a rear perspective view thereof, taken from beneath;

FIG. 3 is a front elevational view thereof;

FIG. 4 is a top plan view thereof; and

FIG. 5 is a side elevational view thereof.
